UNITED STATES PATENT OFFICE.

JAMES A. IRVING, OF NEW YORK, N. Y.

DESIGN FOR A FAN.

48,494.

Specification for Design.

Patented Feb. 1, 1916.

Application filed January 9, 1915. Serial No. 1,471. Term of patent 14 years.

To all whom it may concern:

Be it known that I, JAMES A. IRVING, a citizen of the United States, residing at the borough of Manhattan, city, county, and State of New York, have invented a new, original, and ornamental Design for Fans, of which the following is a specification, reference being had to the accompanying drawing, forming part thereof.

The figure is a front elevation of a fan, embodying the invention.

As shown the fan is characterized by having the appearance of a substantially right-angled cross, longer in one direction than in the other, said cross being formed by four vanes of substantially the same length, arranged in two sets having each two opposed vanes, the opposed vanes of one set being close to the hub of the fan, and the opposed vanes of the other set being carried at a point more remote from the hub.

I claim—

The ornamental design for a fan as shown and described.

JAMES A. IRVING.
